UNITED STATES PATENT OFFICE

ARNOLD GANDER, OF ST. LOUIS, MISSOURI.

DESIGN FOR A FLOUR-BIN STAND.

SPECIFICATION forming part of Design No. 27,784, dated October 26, 1897.

Application filed March 12, 1897. Serial No. 627,250. Term of patent 7 years.

To all whom it may concern:

Be it known that I, ARNOLD GANDER, a citizen of the United States, residing at St. Louis, State of Missouri, have invented and produced a new and original Design for Flour-Bin Stands, of which the following is a specification, reference being had to the accompanying drawing, showing a part thereof.

The figure is a perspective view of my new design.

The leading feature thereof consists of two arms of equal length intersecting each other at right angles at the middle of their length, the upper surfaces of their free ends being provided with raised lugs, as will more fully hereinafter appear.

Referring particularly to the drawing, 11 are two oblong arms intersecting each other at right angles, their upper surfaces being disposed in the same horizontal plane. The upper surface of the free end of each arm is provided with a lug having an inner ver-

tical wall 2, an upper horizontal face 3, lateral vertical walls 4, and an outer inwardly-inclined wall 5 of compound curvature, the upper portion being concave and the lower portion convex. Each arm carries along its under surface near its free end and substantially under the upper lug a caster or roller 6, mounted between the free ends of the outwardly-convex members of a supporting-fork 7. The lugs are all of the same vertical height.

Having described my invention, what I claim is—

A design for a flour-bin stand substantially as set forth.

In testimony whereof I affix my signature in the presence of two witnesses.

ARNOLD GANDER.
